UNITED STATES PATENT OFFICE

116,071

DESIGN FOR AN AUTOMOBILE BUMPER GUARD

Mercer D. Walklet, Akron, Ohio, assignor to American Chain & Cable Company, Inc., a corporation of New York

Application April 12, 1939, Serial No. 84,238

Term of patent 7 years

To all whom it may concern:

Be it known that I, Mercer D. Walklet, a citizen of the United States, residing at Akron, in the county of Summit and State of Ohio, have invented a new, original, and ornamental Design for an Automobile Bumper Guard, of which the following is a specification, reference being had to the accompanying drawing, forming part thereof.

Fig. 1 is a view looking at the automobile bumper guard from the front; and

Fig. 2 is a perspective view of the guard looking at the side.

I claim:

The ornamental design for an automobile bumper guard, as shown.

MERCER D. WALKLET.
